FLOOR TREATING MACHINE OR SIMILAR
ARTICLE

Meyric K. Rogers, La Grange Park, Ill., assignor to Sunbeam Corporation, Chicago, Ill., a corporation of Illinois

Filed July 19, 1965, Ser. No. 86,203

Term of patent 14 years

(Cl. D9—2)

Fig. 1

Fig. 2

FIG. 1 is a perspective view of the design;
FIG. 2 is a top plan view thereof;

FIG. 3 is a front elevation view thereof; and
FIG. 4 is a side elevation view thereof.

The dominant features of the design are shown in solid lines, the broken line partial showing of the handle being for illustrative purposes only.

I claim:

The ornamental design for a floor treating machine or similar article, as shown and described.
